UNITED STATES PATENT OFFICE.

ALBERT DE SAINT CHAMAS, OF CHICAGO, ILLINOIS.

ENVELOP.

No. 797,826.

Specification of Letters Patent.

Patented Aug. 15, 1905.

Application filed August 26, 1904. Serial No. 222,294.

To all whom it may concern:

Be it known that I, ALBERT DE SAINT CHAMAS, a citizen of the United States of America, and a resident of Chicago, in the county of Cook and State of Illinois, have invented certain new and useful Improvements in Envelops, of which the following is a specification.

The main object of my invention is to provide an improved form of envelop adapted for securely retaining its contents and at the same time permitting of being readily opened for inspection of the contents by the postal authorities. I accomplish this object by the device shown in the accompanying drawings, in which—

Figure 1 shows a form of blank sheet of suitable form for making envelopes according to my invention. Fig. 2 is a slightly-modified form of blank for the same. Fig. 3 shows the blank form shown in Fig. 1 with the bottom and side flaps of the envelop folded against the body part and secured together to form the complete envelop, the top flaps being left open for the insertion of contents. Fig. 4 is a similar view, partly broken away, showing one of the flaps at the top of the envelop folded upon itself and representing the envelop in the form in which it is delivered to the user. Fig. 5 shows the second flap folded over the first, being the first step in the operation of closing the same. Fig. 6 represents the same view of the envelop with the closure complete. Fig. 7 is the reverse of Fig. 6. Fig. 8 is an exaggerated section on the line $\alpha\alpha$ of Fig. 7.

In the form shown in the drawings the envelop-blank is substantially rectangular in form, but having its lower corners cut away to form a bottom flap 8 and side flaps 9 and 10. The size of the envelop is determined by the folds along the lines 11, 12, 13, and 14. The folds 11 and 12 are parallel to each other and are located sufficiently inward of the side edges of the sheet to allow the flaps 9 and 10 to overlap. The folds 13 and 14 are parallel to each other and at right angles to the folds 11 and 12. Cuts 15 extend in opposite directions from the points of intersection of the crease 14 with the creases 11 and 12 and toward the upper edge of the blank to form parts 16, extending laterally of the creases 11 and 12, thus forming a central flap 17 and two side flaps 18, the side flaps 18 being secured together when the side flaps 9 and 10 are folded upon the body part of the envelop and fastened together, as shown in Fig. 3. It will

be seen that the envelop now has at its upper end two opposed flaps 17 and 18 and that one of said flaps is considerably narrower than the other, which other flap is provided with parts 16, extending beyond the side edges of the envelop. The gumming of the envelop is indicated by shaded lines, the dotted lines being used to indicate the gumming on the reverse face of the blank.

To close the envelop, the flaps 17 and 18 are first together folded on the crease 19, which is parallel to the crease 14 and lies between the same and the ends of the flaps. The flaps are folded toward the side of the wide flap 18, the narrow flap 17 being outside. The flaps are then again folded in the same direction, this time on the line 14, and the parts 16 are then turned over the side edges of the envelop and secured upon the opposite face of the same, as indicated in Figs. 5 and 6.

If preferred, the envelopes may be delivered to the trade with the first fold in the flap 18 completed and the two parts of said flap pasted together, as indicated in Fig. 4, thus eliminating all possible doubts that the user might otherwise have as to the method of folding the flaps. To close the envelop when the same is in this form, it is only necessary to fold the flap 17 over the top of the folded flap 18, then make a second fold on the line 14 and paste down the flap 16, as before described. Since the flap 18 is secured to the body of the envelop only at its ends and at the fold 14 along the upper end of the envelop, it becomes a keeper of greater rigidity than the body part of the envelop, having its upper edge integral with said body and forming a pocket opening away from the upper edge of the envelop and adapted to receive the flap 17 when said flap is closed and turned back into the pocket. The envelop may be readily opened for inspection by withdrawing the flap 17 from the pocket, and when said flap is returned to the pocket after the inspection the closure is as secure as when it was first made. The flap 18 being first folded upon itself and then upon the adjacent face of the envelop and having its extensions 16 pasted down on the opposite face of the envelop, forms a reinforcing strip or band stiffer than the envelop, extending along one side of the open edge of the envelop and having its ends bent around the side edges of the envelop and secured on the opposite face thereof.

The blank shown in Fig. 2 differs from that

shown in Fig. 1 in having the cuts 15 diverging from the intersections of the fold 14 with the folds 11 and 12 instead of converging from said points, and the parts 16 are so shaped as to be of single thickness in the complete envelop. It is preferred to make narrow flap 17 slightly shorter than the flap 18, as indicated in the drawings.

The feature of forming a pocket along the open edge of the envelop is not broadly claimed herein, but is more fully described and claimed in my copending application, Serial No. 219,082, filed August 1, 1904.

The operation of the device shown will be readily understood from the foregoing description.

It will be seen that numerous details of the construction shown may be altered without departing from the spirit of my invention.

What I claim as my invention, and desire to secure by Letters Patent, is—

1. As an article of manufacture, an envelop having a flap at each side of its open edge, one of said flaps having parts extending beyond the side edges of the envelop, said extended flap being folded upon itself on a line substantially parallel with the open edge of the envelop and being then folded against the body of the envelop along said open edge and having its extended parts folded around the side edges of the envelop and secured on the opposite face thereof, said extended flap thus forming a pocket along the open edge of the envelop on the side opposite the other flap, said pocket open outward and facing away from said open edge and being adapted to receive said other flap when folded over said extended flap and turned back into the pocket, substantially as described.

2. As an article of manufacture, an envelop having a flap at each side of its open edge, one of said flaps having parts extending beyond the side edges of the envelop and said parts

being adapted to extend around the side edges of the envelop when said flaps have been folded upon each other and then together folded against the body of the envelop on the face thereof which has the extended flap, said parts being gummed on the face which is adjacent to the body of the envelop when said parts are in their folded positions, and the other flap being adapted to be withdrawn from engagement with the extended flap without unfolding said extended flap, substantially as described.

3. As an article of manufacture, an envelop having a flap at its open edge, and having a strip secured along its open edge on the side opposite the flap to form a pocket opening outward and facing away from said open edge and adapted to receive said flap when closed and turned back into the pocket, the ends of said strip being folded around the side edges of the envelop and secured on the opposite face thereof, and said flap being adapted to be withdrawn from the pocket without disturbing the ends of said strip, substantially as described.

4. As an article of manufacture, an envelop-blank comprising a rectangular body part, having an end flap and having side flaps adapted to overlap each other when folded against the body part, said side flaps being extended beyond the end of the body part to form, when folded, a second flap opposed to said end flap, and said blank being so cut that one of said opposed end flaps will extend laterally beyond the side edges of the body part, substantially as described.

Signed at Chicago, this 24th day of August, 1904.

ALBERT DE SAINT CHAMAS.
